United States Patent Office

Des. 194,245
Patented Dec. 18, 1962

194,245

BOTTLE

Kenji Yoshizumi, 4980 N. Marine Drive, Chicago, Ill., and George M. Frank, 864 N. Bundy Drive, Los Angeles, Calif.

Filed Mar. 22, 1962, Ser. No. 69,380

Term of patent 14 years

(Cl. D58—6)

FIG. 1 is a front elevational view of a bottle showing our new design;

FIG. 2 is a side elevational view thereof;

FIG. 3 is a top plan view thereof;

FIG. 4 is a bottom plan view thereof.

The rear and side not shown are the same as the front and side respectively shown.

We claim:

The ornamental design for a bottle, substantially as shown and described.
